UNITED STATES PATENT OFFICE

2,346,646

ROTARY MOTOR

Edward Jerome Beech, Sumas, Wash.

Application August 28, 1941, Serial No. 408,674

1 Claim. (Cl. 123—14)

This invention relates to a rotary motor, the general object of the invention being to provide a casing and a rotor therein, with pockets in the periphery of the rotor and abutments or pistons carried by the casing and acting to cause an explosive charge to enter a pocket during the rotation of the rotor with other abutments or pistons acting to compress the charge in the pocket, when such pocket reaches such other abutments with means for firing the explosive mixture and reintroducing it into a pocket in front of another abutment so that the rotor is given an impulse, after which the pocket is exhausted when it reaches another point in its revolution.

Another object of the invention is to provide means for moving the abutments or pistons by the rotation of the rotor and with means for preventing leakage between the parts.

This invention also consists in certain other features of construction and in the combination and arrangement of the several parts to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is an elevational view with one side part of the casing removed and with parts in section.

Figure 2 is a section on the line 2—2 of Figure 1.

Figure 3 is an enlarged fragmentary section on the line 3—3 of Figure 1.

Figure 4 is an enlarged fragmentary section on the line 4—4 of Figure 1.

Figure 5 is an elevational view with the shaft in section.

Figure 6 is an enlarged fragmentary section on the line 6—6 of Figure 1.

In these drawings the casing is shown at A and the rotor at B. The casing is formed of two halves, the rim portions of which have stepped inner edges as shown at 1 and the two parts are fastened together by the bolts 2. The rotor is connected with a shaft 3 which passes through the bearing parts 4 at the centers of the sides of the casing and the rotor is provided with a plurality of arcuate-shaped pockets 5 in its periphery. The motor is shown and described with the rotor provided with four pockets but it will be understood that the motor can be constructed with any suitable number of the pockets and associated parts.

A pair of substantially opposed inlet ports 6

are formed in one side of the casing and these ports are connected with suitable carburetor means and an air escape port 7 is arranged adjacent each of the inlet ports, a suction piston or abutment 8 extending between each pair of the ports 6 and 7. An exhaust pipe 9 enters the casing, through the rim thereof adjacent each of the pistons or abutments 8, these exhaust pipes being connected with suitable manifold means. A pair of substantially oppositely arranged explosive chambers 10 are connected with other portions of said side of the casing and each of these explosive chambers is of U-shape with its ends in communication with the interior of the casing by the ports 11 and 12. A spark plug 13 extends into each chamber and these spark plugs are connected with a suitable ignition system. A check valve 14 is located in each chamber 10 adjacent the inlet end thereof. A compression piston 15 is located adjacent the inlet end of each chamber 10 and a pressure piston 16 is located adjacent the outlet end of each chamber. All these pistons or abutments are each formed of a plurality of plates 17 which slidably pass through slots in the rim of the casing and through bushings 19 attached to the exterior surface of the casing, each group of plates having its outer end fitting in a cap 20 with resilient means 21 placed between the cap and said outer ends of the plates. Each piston or abutment has the ends at its cap connected to arms 22 by springs 23 with the inner ends of the arms having stub shafts 24 attached thereto, these shafts passing through openings 25 in the sides of the casing and rollers 26 are connected with the inner ends of the shafts and engage cam grooves 27 formed in the sides of the rotor. Thus during rotary movement of the rotor the arms 22 and springs 23 variably tension the cap 21 to correspondingly tension the pistons to move inwardly so that the inner ends of the pistons will bear against the rotor and bottoms of the pockets with uniform pressure as the pockets and intermediate peripheral portions of the rotor come opposite the pistons. Matching grooves are formed in the sides of the casing and in the sides of the rotor for receiving the rings 29 to prevent leakage and radially extending L-shaped packing members 30 are placed in grooves in the inner walls of the casing and are pressed against the rotor by the spring strips 31, see Figure 6, to prevent leakage from the combustion chambers through the exhaust means and vent ports 32 are formed in the casing in rear of each pressure piston 16. While the rotor may rotate in either direction

the operation of the engine is described with the rotor operating in a counter-clockwise direction as shown by the arrow *a* in Figure 1. As will be seen during the rotary movement of the rotor as the upper pocket in Figure 1 passes the suction piston 8 a suction created in the pocket by the piston 8 will draw an explosive mixture through the port 6 and any air in the pocket will escape through the vent port 7. Then as this pocket reaches a point where it will be engaged by the compression piston 15 the explosive mixture will be forced by the piston 15 through the port 11 into the combustion chamber 10 where it will be exploded by a spark from the plug 13 and then the exploded gases will enter the pocket through the port 12 and in front of the pressure piston 16. Air or other fluid in the pocket in rear of the piston 16 will escape through the vents 32. The action of the expanding gases in the pocket against the piston 16 will give the rotor its impulse and then the pocket reaches the lower exhaust pipe 9 through which the exhaust gases will pass and then another charge is drawn into the pocket through the lower port 6 while air in rear of the piston 8 will pass through the vent 7. Of course, the explosive mixture drawn into the pocket will be caused to enter the second combustion chamber where it will be exploded by the spark plug in this chamber and then the gases will enter the pocket in front of the pressure piston 16.

Thus a plurality of impulses is imparted to the rotor to rotate the same.

It is thought from the foregoing description that the advantages and novel features of the invention will be readily apparent.

It is to be understood that changes may be

made in the construction and in the combination and arrangement of the several parts provided that such changes fall within the scope of the appended claim.

Having described the invention, what is claimed as new is:

5 In a rotary engine, a casing, a rotor in said casing having concave peripheral pockets therein circumferentially spaced around said rotor and forming together with the inner wall of the casing fuel containing chambers, means coating with said pockets in one direction of rotation of said rotor to cause suction in said chambers and including a fuel inlet port in one side of the casing through which fuel is drawn into said chambers under the action of suction created therein, abutments slidably mounted in said casing in advance of said first means operative to enter said pockets as the latter are rotated past the same to form partitions therein forcing the fuel in said chambers rearwardly and thereby compressing the same, means providing for passage of the compressed fuel from said chambers from the rear of the partitions back into the chambers in front of the partition, means to ignite such fuel within said by-passing means, and means for variably tensioning said abutments to cause the same to ride on said rotor and enter said pockets with uniform pressure against the rotor and bottoms of the pockets comprising caps at the outer ends of the abutments, cam grooves in the opposite sides of the rotor, arms slidably mounted on opposite sides of the casing and provided with angular ends projecting into said grooves, and springs connecting said arms to said caps.

EDWARD JEROME BEECH.
